William Whittmore

The Schedule referred to in these Letters Patent and making part of the same containing a description in the words of the said William Whittmore, himself of his improvement in the machine used for separating the seeds from Cotton commonly called the roller gin.

To all to whom these presents shall come,

William Whittmore the younger of West Cambridge in the County of Middlesex and Common wealth of Massachussetts gentleman sends greeting: Be it known that the said William Whittmore have invented made and applied to use a new and useful improvement in the machine used for separating the seeds from Cotton commonly called the roller gin. which new invention and improvement is specified and described in and by these presents: figure numbered one, is the drawing made annexed which drawing is to be taken and considered as a part of this Specification represents a side view of the ^{said} machine. figure numbered two in the said drawing represents a sectional view of the said machine and figure numbered three represents a birds eye view of the said machine. The same parts of the machine are designated by the same letters in all the said figures. The sizes dimensions and proportions herein given of the several parts of the machine are those of the size parts of a machine which I have applied to use and deem in that regard best adopted for the purposes herein mentioned. A designates the balance wheel attached to the end of the lower steel roller a. which wheel is of cast iron and seventeen inches and a half in diameter. B. B. B. designates the sides and bottom of the machine which are also of cast iron. the sides are seven and a half inches wide, seven eighths of an inch thick at the top and one and three quarters inches thick at the bottom and thirteen inches in height.

① D. 4. a. m.

264

from the bottom to the top of the peak. The sides are about nine inches apart from each other and are fastened to the bottom each by two screws passing up through the bottom parts of the frame into the sides. C.C. designates pieces of iron eleven inches and one quarter long and an inch and three quarters deep in the deepest part, and two inches thick in the thickest part. One of these pieces of iron is attached to one side of the frame B. on the outside thereof by means of a bolt S. with a screw at the end, which bolt passes through a hole near the end of the piece of iron C. and screwed into the projection D. which forms a part of the said B. and said piece of iron is movable upon the bolt S. as upon a hinge or bearing. The other of these pieces of iron is attached in the same manner by a bolt S. to the other side of the frame B. on the outer side thereof. In each of these pieces of iron C.C. is a slot six inches and a quarter long and three quarters of an inch wide made entirely through the whole depth of the same pieces of iron from the top to the under sides thereof. D.D. designates pieces of iron seven inches and a half at the longest part one inch and seven eighths in thickness, and one and three quarters inches deep. One of these pieces of iron is fastened to the projections D. on one side of the frame B. on the outside thereof under one of the pieces of iron C. above described by a screw at each end, the other of these pieces of iron D. is fastened in like manner to the projections D. on the side of the frame B. on the outside thereof under the other piece of iron C. above described. These pieces of iron D.D. have slots made through them from the top to the under sides thereof, in a similar manner and of similar size corresponding to the slots in the pieces of iron C.C. above described. H.H. designates two parts of cast iron eight inches

200.

and three quarters high and one and fifteen sixteenths
of an inch wide at the bottom and tapering to one and seven
sixteenths of an inch at the top and all the same distance
apart from each other as the sides above described and the
centers of these posts are about eight inches and three
eighths of an inch distant from the sides. B. D. designates
what I term the cleaver and for the purpose of taking the cap-
ton from the band E. It is made of hard wood and is
an octagon form four inches and a half in diameter
from side to side and nine inches long and has guides
on which turn six movable studs screwed to the posts
B. B. which studs have slots in them so that they may
be moved up and down and fixed by the screws at
any convenient place so as to bring the cleaver E. suffi-
ciently near to the band. H. G. designates a roller of hard
wood about two inches and a half in diameter and
nine inches long over which the band E. passes. This
roller has guides which turn on bearings in the heads
of the bolts C. C. which pass through the upper ends of the
posts B. B. and are four inches and a half long on the
outer ends of which bolts' screws are cut for about one
inch and a half to which thumb nuts are adapted
so as to bring the heads of the bolts nearer or further
distant from the posts B. B. in order to regulate the
tightness of the band E. The roller G. is directly
above the cleaver H. G. designates an undrilled band of
real leather nine inches wide which passes over the
steel roller H. and the wooden roller G. sufficiently
tight to cause it to revolve. It is formed by passing
down each end of a suitable piece of real leather and
causing the ends to lap over each other so that the band
may be of an uniform thickness and connecting them
together with a band made of the Russian Spring
steel.

displaced in brandy and water or water. After the
 band is thus formed, a coat of glue is to be put over the
 whole outside thereof, with a brush, and after the glue thus
 put on is dry a coat of the Russian Vinglass thus dissolved
 as aforesaid is to be put over it with a brush in order to form
 a hard crust upon the surface of the leather and to make
 the leather more hard and firm. That I term the guard
 which is made of thick sheet iron is designated by I. It is
 made four inches wide and nine inches long and laps
 over at the top about and inch so as to be fastened and
 kept in its place by screws & which pass through it into
 the sides of the frame B.B. above described. The lower edge
 of this guard is made to come nearly in contact with the
 upper steel roller b. about the center of the side thereof
 past the roller C. It is fixed about thirty one degrees from
 a perpendicular the top inclining towards the roller C. &
 is designed to prevent the cotton after having passed beneath
 the upper steel roller b from being carried round and back
 upon and by said roller, K. designates the a pulley for
 driving the machine fixed upon the end of the lower
 steel roller a. or rather upon an extension of that roller
 six inches in diameter and three inches thick and
 made of hard wood. L.L. designate projections being
 spurs of the sides B.B. herein before referred to. a. de-
 signates the lower steel roller two feet two inches and
 a half in length from end to end and one foot four inches
 and three eighths of an inch between the pinion h. on the
 one side and the driving pulley k. on the other side. And
 the diameter of this roller between the bearings is thirteen
 and one half inches. It bears and turns upon the friction
 rollers c. f. c. f. on each side of the machine, and is
 twelve inches and three eighths in length between these two
 bearings. " with these bearings ground a out about one six
 teenth

tenth of an inch deep and five eighths of an inch wide for
 the friction rollers to work in. The band H before mentioned
 passes over this roller and is carried around by it, by
 the bearing and pressure of the upper roller b, upon it. The
 roller a, has a large pinion, h, near one end with twelve
 teeth close to the pulley, i, which mesh into a large pinion
 g, upon the upper roller b, having the same number of teeth
 next to the pinion h. This steel roller a, has upon it a fix-
 ed pulley, i, of hard wood, three inches and one half in di-
 ameter and one inch and one eighth in thickness, over
 which the band H, passes in order to turn the pulley k,
 attached to an extension of one of the guides of the chain.
 It, so as to cause it to revolve when the roller a, is put
 in motion. b, designates a steel roller fifteen inches and
 five eighths long, from end to end, and twelve inches and
 three eighths between the bearings and thirteen eighths
 of an inch in diameter between the bearings. At the bear-
 ings it has grooves cut in a similar manner and for a
 like purpose as those on the other rollers, a. If bears
 upon the band H which passes over the lower roller a,
 and also up against the friction rollers c, d, c, d, and
 has a pinion g, on one end with twelve teeth which
 mesh into the pinion h, on the roller a, so that the
 upper roller b may be turned by means of these pin-
 ions by the turning of the lower roller a. This roller is
 of cast steel and highly polished to prevent the wood
 from being driven through between it and the band
 on the lower roller a. c, d, c, d, designate friction
 rollers of cast iron, each two inches and seven eighths
 in diameter and five eighths of an inch thick, two
 of which turn in the slots before described in each
 of the pinions of cast iron. C, c, upon fixed steel balls
 or a, which pass through one side of the pinions of cast iron.

268

C, and are screwed into the other by means of a screw cut at the end of the bolt, These rollers bear upon the upper steel roller, b, when grooves are cut as before mentioned to prevent the roller from sliding from its place.

c, f, e, f, designates similar cast iron friction rollers of similar dimensions, two of which turn in each of the slots before described in the pieces of cast iron D, D, upon similar bolts m, m, upon which friction rollers the under steel roller, a, bears at the grooves cut in it for a like purpose as those cut in the upper roller, and h, are the pinions before referred to and described, i, designates the pulley before described for communicating the motion of the roller a, to the element F,

h, designates the pulley before referred to attached to the extension of one of the guides of the cleaver II. This pulley is of hard wood six inches and a half in diameter and one inch and one eighth thick, and it is fastened on the end of the extended guide by means of a screw and nut, l, designates the extension of the guide before mentioned made of wrought iron m, m, designate screws five inches long and about three-eighths of an inch in diameter which at the lower end are screwed into the projections m, m, being parts of the sides B, B, before referred to, the upper ends of which screws pass through the pieces of cast iron C, C, before referred to so that by means of thumb nuts screwed upon the upper ends of these screws the pieces of cast iron C, C, may be screwed down so as to regulate the bearing and friction of the friction rollers c, d, e, f, upon the upper steel roller m, m, designates the projections being part of the sides B, B, for retaining the ends of the screws just mentioned, o, o, designate the bolts before referred to and described l, p, p, designate the projections before

before referred to being part of the sides B. B. The pieces of iron C. C. should be screwed down by means of the screws and thumbscrews before referred to so as to make the friction roller c. d. c. d. bear sufficiently hard upon the polished steel roller b. to cause it to bear sufficiently hard on the band H. to make it revolve and draw the cotton through between it and the band H. and at the same time to prevent the seeds from passing through and thereby to separate them from the cotton. By means of the friction rollers the machine is moved much easier and they prevent the steel rollers a. and b. from being heated so as to injure the band or the cotton when the machine is moving with great velocity. The machine may be driven by steam, horse, water or any sufficient power at the rate of about five hundred revolutions a minute. It is deemed best that the rollers a. and b. should be of about the same diameter. The rollers ought to be of the best cast steel ~~and iron~~ in order that they may be stiff and not liable to spring as will iron or other metals when the rollers are of the above size and dimensions. The size above described for the roller a. is deemed best, for if it were in any considerable degree smaller it would be liable to spring in the middle, and thereby cause the cotton to be clogged in the machine, and of it were in any considerable degree larger the seeds would be liable to be driven in by it. If the roller b. being small and ~~and iron~~ made and highly polished it does not act upon the seeds so as to wear them out. The clevis H. should be made to revolve as near the band H. as may be without touching it when the machine is put in operation. By means communicated to the party K. the lower steel roller a. is thereby enabled to revolve and by means of the spring

before described, to turn the upper steel roller b, which bears hard upon the band H, and thereby to cause the band H to revolve and the roller C, with it, and at the same time by means of the pulleys in it, the band M, the cleave P, is made to revolve. The machine is fed by hand in the same way as the roller gins now in use. The cotton passes through between the steel roller b, and the band H, which passes over the wooden roller a, and the wooden roller C, and after passing through as aforesaid the cotton passes along on the band H, ^{and} is taken off by the cleave P, which in revolving strikes against it. A tin funnel with a long tube may be placed under the steel roller b so as to receive the seeds as they fall and conduct these into a receptacle prepared for receiving them. Instead of the rollers a, b, c, d, the friction rollers may have a slot fixed in them with guageons to revolve in boxes or slots made in the pieces of iron C. C. and D. D. before described, and this mode is deemed preferable on account of its being rather more easy to apply oil to the guageons.

The pinions g, h, and also the friction rollers may be made of wrought iron or other suitable metal, but will be better if made of steel than of other metal. The size, dimensions and proportions of the several parts of the machine, may be somewhat varied at discretion excepting however that the steel rollers a and b cannot be advantageously made longer or larger or smaller in any considerable degree than the dimensions above given for the reasons before stated, but these rollers may be made shorter than the above dimensions and the rest of the machine, or adapted to them and they will in this case answer the purpose tolerably well, but the length above given is deemed preferable. Rollers may be made of hard and stiff material other than steel that

will answer some useful purpose, especially when the machine is not driven with great velocity. But in this case they ought at least to be three inches shorter to prevent their springing or breaking: and for a like reason the balance wheel ought to have a yudgeon on the outer side thereof, turning in a box in a fixed part or frame over the under roller bed of steel and the upper roller only of hard and stiff metal, which will also answer some useful purpose, in which last mentioned case the yudgeon to the balance wheel will not be necessary, unless a heavier balance wheel than that above described is used; the above described balance wheel weighing about eighteen pounds. If a balance which considerably larger or heavier be used it will be expedient to have this exterior yudgeon to turn in a box in a fixed part as aforesaid, even with steel rollers such as above described. But a metal so strong, hard and stiff is required for the above purpose, that the steel rollers such as first above described are deemed far preferable to any other, as being less liable to spring or break, than any other rollers of the same size and length. What I claim as now and of my invention and all which I claim as my invention and improvement in the above machine is the construction, application and use of such guard, as I term it as is herein before described and referred to, for the purpose aforesaid, and the construction, application and use of such metallic rollers as aforesaid designated by a, and b, in the drawing hereto annexed with a band over the lower roller a, in connection and combination with such friction rollers c, d, c, d, and c, f, f, f, as aforesaid for the purpose of separating the seeds from cotton as aforesaid.

Establishing that the above is a true description of my
said record, signatures and fingerprints I have initialed
this day.
